(57) **CLAIM**

I claim the ornamental design for a magnetic cable organizer, as shown and described.

DESCRIPTION

FIG. 1 is a perspective view of a magnetic cable organizer, showing my new design in a rolled configuration around a bundle of cables;

FIG. 2 is a perspective view thereof, shown rolled around a person's arm;

FIG. 3 is an alternate perspective view thereof;

FIG. 4 is a perspective view thereof, illustrated in an unrolled configuration;

FIG. 5 is a right-side elevational view of FIG. 4;

FIG. 6 is a left-side elevational view of FIG. 4;

FIG. 7 is a front elevational view of FIG. 4;

FIG. 8 is a rear elevational view of FIG. 4;

FIG. 9 is a top plan view of FIG. 4; and,

FIG. 10 is a bottom plan view of FIG. 4.

The broken lines showing a bundle of cables in FIG. 1 and a person's arm in FIG. 2 depict environmental matter and form no part of the claimed design.
